CLAIM

The ornamental design for a firearm scope mount, as shown and described.

DESCRIPTION

FIG. 1 is a top, front, left side perspective view of a firearm scope mount according to the present disclosure;

FIG. 2 is a top view of the firearm scope mount of FIG. 1; FIG. 3 is a bottom view of the firearm scope mount of FIG. 1;

FIG. 4 is a front view of the firearm scope mount of FIG. 1; FIG. 5 is a rear view of the firearm scope mount of FIG. 1; FIG. 6 is a left side view of the firearm scope mount of FIG. 1; and,

FIG. 7 is a right side view of the firearm scope mount of FIG. 1.

The broken lines in the Figures are included for the purpose of illustrating portions of the article and form no part of the claimed design.

1 Claim, 4 Drawing Sheets
